UNITED STATES PATENT OFFICE.

EUGENE KEZY, OF CHICAGO, ILLINOIS.

DESIGN FOR A SHOE.

Application filed August 4, 1922. Serial No. 3,290. Term of patent 7 years.

To all whom it may concern:

Be it known that I, EUGENE KEZY, a subject of the King of Roumania, residing at Chicago, in the county of Cook and State of Illinois, have invented a new, original, and ornamental Design for Shoes, of which the following is a specification, reference being had to the accompanying drawing, forming a part thereof.

I claim:

The ornamental design for a shoe, as shown.

EUGENE KEZY.
